UNITED STATES PATENT OFFICE.

JAMES WALKER SIMONS, OF PORT CHESTER, NEW YORK.

SEWING-MACHINE ATTACHMENT.

SPECIFICATION forming part of Letters Patent No. 569,773, dated October 20, 1896.

Application filed February 26, 1896. Serial No. 580,808. (No model.)

To all whom it may concern:

Be it known that I, JAMES WALKER SIMONS, a citizen of the United States, residing at Port Chester, in the county of Westchester and State of New York, have invented certain new and useful Improvements in Sewing-Machine Attachments, of which the following is a specification.

This invention relates to attachments for sewing-machines, and particularly to what are known as "fold-gages."

The object of my invention is to overcome the defects inherent in constructions now known to me and to provide a fold-gage having a vertical adjustment preferably on the face-plate or head of the sewing-machine frame, although it may be located on any other convenient part of the frame, and comprising a long stem or body to be adjustably fitted in a clamp of suitable construction on said head and two right-angular bent portions at its operative end, one of said bent portions serving to smooth out wrinkles, &c., from the material and the other operating as the fold-gage proper.

In the drawings accompanying and forming part of this specification, Figure 1 is a perspective view of part of a sewing-machine frame, showing the fold-gage in position thereon. Fig. 2 is a plan view of the clamp by which the fold-gage is adjustably supported. Fig. 3 is a detail view of the guide for the stem of the fold-gage, a portion of the frame being shown in section. Fig. 4 is a perspective view of one of the interchangeable fold-gages; and Fig. 5 is a sectional view showing how the gage operates with the usual hemmer, which may be substituted for the presser-foot shown in Fig. 1.

Similar characters designate like parts in all the figures of the drawings.

The numeral 1 represents the usual head part of the frame of a sewing-machine, 2 the needle-bar, and 3 the presser-bar of such machine.

The numeral 4 represents the improved fold-gage, comprising a long stem or extension 4', a right-angular bent portion 4², and another portion 4³, bent at right angles to the part 4².

The numeral 5 represents a clamp having a stem 5' secured by a screw or other fasten-

ing device 6 to the head of the machine and also having a thickened split portion 5², perforated at 5³ to receive the stem of the fold-gage, said perforation being large enough to accommodate different sizes of gages having stems of varying diameters. A screw 7 is provided which bears against the gage, and another screw 8 is employed for adjusting the jaws of the clamp, and by means of these screws the fold-gage is fixedly secured in position. An additional clamping and guiding means for the stem of the fold-gage is shown, consisting of a bracket 9, secured to the machine-head or face-plate by a screw 10, said bracket being provided with two perforated ears or lips 9', through which the stem passes. The perforations in said ears are shown as somewhat larger than necessary to fit the stem of the fold-gage in position for the purpose of guiding and holding fold-gages having stems of different diameters. The screw 10 engages with a thread or nut in bracket 9 and passes loosely through the head or front plate of the machine, thereby serving two purposes—one of clamping the bracket to said head or front plate and the other of securing the fold-gage above the lower clamp 5, so that said gage will be fixedly held in the desired adjusted position to suit the thickness of the material being sewed. The point of screw 10 bears on that portion of stem 4' located between the arms of the bracket, and hence tends to slightly deflect or bend the same between said arms, thereby holding said stem fixedly in position above the lower clamp and rendering the fold-gage secure against displacement.

While the guiding and holding bracket is shown as located about midway the face-plate, yet, as is obvious, it may be placed near the top of said plate or at any other convenient point thereon either above or below the clamp 5. It is also obvious that other forms of clamps and guides may be employed for guiding and holding the fold-gage in position at two different points on the machine-head without departing from my invention.

At Fig. 4 is shown a fold-gage of greater dimensions than that represented in Fig. 1, and it is to be understood that a series of interchangeable fold-gages are to be provided to suit any width of fold desired.

In Fig. 5 is represented a common form of hemming presser-foot 11, which may be placed on the presser-bar as a substitute for the presser-foot shown in Fig. 1, if deemed necessary or advisable. The hemming presser-foot is provided with the usual needle-hole, curling-finger 12, passage-way 13, and solid separator 15, and other common features unnecessary to mention, and with a shank 16, corresponding with that of the other presser-feet of the machine on which the attachment is to be used, and this may be any type of sewing-machine.

At 17 is represented the cloth or other material being sewed, 17' representing the fold thereof.

A fold-gage to suit the fold or hem desired having been placed in position, the cloth or other material is placed under the presser-foot and a fold of the desired width is turned over the effective portions 4³ and 4² of said gage. The presser-foot is then lowered and the material is passed beneath the needle and is stitched in the usual manner, the part 25 4³ of the gage serving to guide the fold and the part 4² to level and smooth the material on the plate of the machine as it passes beneath the needle.

Having thus described my invention, what 30 I claim, and desire to secure by Letters Patent, is—

1. The combination with a sewing-machine, of two guiding devices detachably connected to said machine at points one above the other; and a fold-gage vertically adjustable in said guiding devices. 35

2. The combination with a sewing-machine head, of a fold-gage having a relatively long stem; and clamping means for said stem, located at different points on the head, whereby 40 the device is maintained in vertical alignment.

3. A fold-gage comprising an elongated vertical bar bent at its lower end to form two right-angular portions, one extending transversely to the elongated bar and the other extending transversely to said elongated bar and to its other angular portion. 45

4. The combination with a sewing-machine head, of a perforated split clamp attached to said head; a pair of clamping devices carried by said clamp; a fold-gage having a perpendicular stem extending through said perforation and secured therein by said clamping devices; and a second clamp also secured 50 to the head and engaging the stem at another point in the length thereof. 55
